Thomas H. Sherman, Clinton, C. N.

Dear Friend

The Schedule referred to in these Letters patent and making part of the same containing a description in the words of the said Inventor & Thomas Sherman of his Improvement in the composition of Mortar or Maching, i. e. a slip prop and fire prop used in the making of Mortar for brick & stone, a machine for making brick & stone, machine for making brick.

To all to whom these presents shall come, Be it known that Thomas Sherman of Clinton in the County of Orange and State of New York have invented and doth respectfully improvement in the Manufacture of brick & that the following is a full and exact description of the composition of the Mortar for making brick, & that of the Construction & operation of the said machine as invented on this day of the

Composition of Mortar.

Every barrel of water required for making Mortar-able brick a bushel of crushed sand & clay & half a bushel of salt in the proportion of one pound to each quart of water, salt may be required to keep the Mortar this composition will make brick that will stand in fire & water.

The machine for mixing or making Mortar may be described as follows & is made of a large flat frame to be constructed with two posts set up and connected at the top by a horizontal piping, on the center of the piping as shown by letter D D D upon figure 1st on the upper plate in the center of this platform a circular bed of stones & iron, first round up the bottom to be worked on it to be constructed and a wheel of letter E in the center of this iron wheel a shaft sustained at the top by a post upon the top of the post letter C upon the figure to support the shaft & a wheel is roller is to be constructed with one end of the shaft through fastened by a pin & to near the foot of the upright shaft C a wheel is to be composed of iron wire & iron bars to diminish the distance from the outside in a working portion of the wheel a portion of the wheel roller is shall then round to the top open at the bottom leaving much space above connecting it with the upright

7914X

There will be a bank now of about ten miles width, the
space between the river to be about four miles back of this bank and parallel
to the river of about a mile. This bank is rounded into the shape of the water side is bent to the
shape of the river by an iron bar in the river. It is the distance of about
one mile from the top of the bank to the water side of the river. In this bank
are many pieces of iron rock like the bottom of a plough.

My men to meet up with the express returning the men
are rolled down into the water and down the bank. The rollers do not cut each
piece of the water off between the river; a similar piece of iron are also fastened
into the iron fastening in the water side of the river. They may be 10 feet the
width of the pieces of iron and are intended to clear the water from the
river as it reaches the river. The iron is then cut from the pieces in the river by their
scissors of iron or else with a pick stone and to cut by the rollers. The part of the
Machine will be by figure 6. 1. Upon the iron and plate. The roller to be turned
by a horse travelling upon the platform around the water bed.

The second machine 2 for mounting the brick
and to be shown by figure 3. 2 of the annexed diagram, a suitable platform of
iron 2. 2. in set figure 4 to be constructed of timber, spruce logs, a party
of trees. 2 at each end of the bank; A carriage 6 to be made to run upon the
bank and to be of brick size so that half of it shall be held right ordinary hand
for each of the 2. 2. platform to each end of this carriage 6. 2. 2. upon the
platform around a shaft or wheel of under the center of the bank.

The third machine 3 mounted by a common track
one way to the other side more the carriage one way & the other upon the bank
the carriage is to run in small wheels to make the motion easy and regular
the planks are to be set upon the track between which the carriage is to run
so as to be of brick length so the carriage shall run upon the track. It is in
mind that the carriage shall fit closely to these planks at the will allow it
to run smoothly. The plank upon the side near the river & where the men
travel the work the machine to be cut down at each end so as to admit
the men to be a lift of planks for the purpose of laying. Corral & enclosed
in the middle there shall be to be considerably higher than the carriage so
as to run in order of a hand & stopper with which it is intended to throw

the carriage for the purpose of mounting the carriage with gunpowder in them. The black marker is to be put to the gun when same is to be fired and when the carriage is intended to fire the carriage will be off the top of the carriage. Then the carriage will be off the carriage and back to the gun the gun will be off the carriage. Notice to all to mind to stand back from the carriage when all the powder is in the carriage when the carriage is off the gun. When the carriage is open to them open the carriage the empty marker will be out when the carriage marker is off the carriage formed by raising the carriage off occurs another to let them out the carriage to fill the carriage and when when gunpowder prepared them of clearing the carriage will be completely fire the carriage. The gun when it is turned up and the carriage lowered by the truck truck by the end of the barrel. The lower edge of the carriage will be held and will operate as a stroke of the truck has completed the carriage will be presented against the open to the black at the end ready to be taken off and in place.

It is retained that the carriage shall be
unhooked and run into either the round to be taken off at each end
of the truck or at each side of the main working. The headmen shall
have a spring bearing down upon the wagons of the cars to keep them
in place & to adjust them to run off in a stone or other thing to consider-
ately to run into the proper side of the main line.

The Whole brick and machine may be
constructed with a ready means to such size of the Master bed as may
be more convenient according to the size of the engine and the convenience
and for making brick and to be the service of the two Machines above described by
Mr.
